UNITED STATES PATENT OFFICE.

NIELS A. CHRISTENSEN, OF MILWAUKEE, WISCONSIN.

COMPRESSOR MOUNTING.

Application filed November 9, 1925. Serial No. 67,923.

The invention relates to compressors, and more particularly to compressors for the air-braking-and-starting equipment of automotive vehicles.

Heretofore it has been the general practice to mount the compressor adjacent the engine and drive the same from auxiliary shafting associated with the engine, such as the magneto drive shaft. The object of this invention is to provide a compressor in which the crankcase is formed by the removable front end cover plate of the engine, with provision for inspecting the bearings of the compressor upon removal of the compressor cylinder and said cover plate, and more particularly to provide certain modifications over the construction shown in my copending application Serial No. 47,933, filed August 3, 1925.

The invention further consists in the several features hereinafter set forth and more particularly defined by claims at the conclusion hereof.

In the drawings, Fig. 1 is a front elevation view of an automotive engine equipped with apparatus embodying the invention;

Fig. 2 is a detail vertical sectional view taken on the line 2—2 of Fig. 1;

Fig. 3 is an enlarged view of a portion of the front cover plate, with the compressor parts shown in a section taken along the line 3—3 of Fig. 2;

Fig. 4 is a detail sectional view taken on the line 4—4 of Fig. 2, with the piston and front end of the crank shaft omitted.

In the drawings the numeral 5 designates an internal combustion engine of the automotive type, in which the timing gears for the cam shaft drive and other gears for the generator drive and the fan are mounted at the front end of the crankcase 6 of the engine within a housing formed by the engine crankcase and the removable front cover plate 7 which is secured to the crankcase by bolts 7'. According to the present invention, the front cover plate 7 is specially designed to form the crankcase 8 of the compressor, and has a mounting pad or portion 9 formed thereon to support the cylinder 10 of the compressor. A front extension 11 of the crank shaft of the engine extends through the housing or crankcase into a recess 12 in the front end trunnion bearing 13 of the engine. The main bearing 14 for the forward crank throw of the engine crank shaft is within the engine crankcase proper

adjacent the front cover plate and a portion of said bearing is shown in Fig. 2.

The front end of the crankcase of the engine is specially designed to provide a pad or face portion 15 against which the compressor cylinder supporting flange 16 of the cover plate abuts. The compression cylinder 10 has a flanged base 17 which at its rear edge 18 also abuts against the pad portion 15 and forms a tight joint therewith. The flanged base 17 is provided with bolt holes through which the hold-down bolts 19 pass into tapped holes 20 in the pad portion 9 of the front cover plate. The holes in the base 17 for the bolts 19 are large enough so as to permit a slight lateral movement of the base 17 relative to the pad 9, during assembly, so that just before the bolts 19 are finally tightened up the base 17 may be moved laterally to bring its edge 18 against the pad portion 15 and maintain it in this position by means of bolts 21 having threaded engagement with a tapped hole 21 in the flange 16, and provided with washers 22 engageable with the front face 23 of the base 17 and exerting pressure thereon. Thus, the cylinder 10 is removably secured to the pad 9 and abuts on one side of its base against the engine crankcase.

A piston 24 works in the cylinder of the compressor and is operatively connected to the main extension 11 of the crank shaft 25 of the engine by means of a wrist-pin 26 and connecting-rod 27, with its adjustable big end-bearing 28 formed as an eccentric strap to fit over the crank pin 29 formed in the extension 11 which is keyed at 30 to the end of the crank shaft 25 and held against endwise movement by a screw 31 extending into the end of said shaft.

The inlet and exhaust valves of the compressor are not shown in detail, but may be of any suitable construction.

The pad portion 9 of the front cover plate has a bore 32 formed therein communicating with the crankcase 8 and a slot 33.

With this construction the piston 24 of the compressor is driven by the engine crank shaft to compress air in the compressor cylinder and expel it to the reservoir. As the cylinder is removable independent of the cover plate, the piston rings and the wrist-pin may be readily inspected or removed, when desired, by taking off the cylinder 10. In case any adjustment or renewal of the big end-bearing of the connecting-rod 27 is

necessary, the removal of the cylinder 10 permits the taking off or partial removal of the cover plate 7 by an endwise movement of said plate, and thus permits ready access to 5 said big end-bearing, the slot 33 preventing any interference between the connecting-rod and said plate during its removal.

Inasmuch as the crankcase 8 of the compressor is an extension of the main crankcase of the motor, the lubricating system for the compressor may use the same lubricating oil as the motor, and the oil dripping or coming down from the walls of the compressor cylinder below the piston will serve 10 to oil the big end of the connecting-rod and find its way into the crankcase of the motor, and return to the main oil sump of the engine. As shown, the cylinder head of the compressor has a cooling space 34 into which 15 the lubricating oil of the main engine is forced and from which the oil flows through a passage 35 into the lower end of the cylinder and then to the crankcase 8. The oil from the passage 35 may flow into a recess 20 36 in the pad 9 before dripping down into the crankcase, and the lower end of the piston moves down into this recess.

I desire it to be understood that this invention is not to be limited to any specific 30 form or arrangement of parts except in so far as such limitations are specified in the claims.

What I claim as my invention is:

1. In an automotive type engine, the combination with the crankcase of the engine having a pad portion at its front end, of a detachable front cover plate having a part forming the crankcase of an air compressor and a compressor-cylinder-supporting portion for said compressor, and a compressor cylinder having its base portion mounted on said cylinder-supporting portion of said front cover plate and its rear edge abutting against said pad portion of said engine 45 crankcase.

2. In an automotive type engine, the combination with the crankcase of the engine having a pad portion at its front end, of a detachable front cover plate having a part 50 forming the crankcase of an air compressor and a compressor-cylinder-supporting portion for said compressor, a compressor cylinder having its base portion mounted on said cylinder-supporting portion of said front 55 cover plate and its rear edge abutting against said pad portion of said engine crankcase, and means for forcing said rear edge into tight engagement with said pad on said

engine crankcase and for maintaining it in this position.

3. In an automotive type engine, the combination with the crankcase of the engine having a pad portion at its front end, of a removable front cover plate secured to said crankcase and having a compressor crankcase portion into which the crank shaft of the engine extends, said cover plate also having a compressor-cylinder-supporting portion, a cylinder removably mounted on said supporting portion and having an edge 70 forming a tight joint with said pad portion of said crankcase, a piston working in said cylinder, a driving connection between said piston and that portion of the crank shaft extending into said compressor crankcase, said supporting portion having an opening, covered by said cylinder, to accommodate said driving connection and to permit the removal of said cover plate upon the removal of said cylinder without disconnecting 80 said driving connection.

4. In an automotive type engine, the combination with the crankcase of the engine having a pad portion at its front end, of a detachable front cover plate having a part 85 forming the crankcase of an air compressor and a compressor-cylinder-supporting portion for said compressor provided with a slot whose open end terminates at said pad portion, and a compressor cylinder having its 90 base portion mounted on said cylinder-supporting portion of said cover plate and covering said slot with its rear edge abutting against said pad portion of the engine crankcase to close off the open end of said 95 slot.

5. In an automotive type engine, the combination with the crankcase of the engine, of a removable one-piece front cover plate having a compressor crank case portion and a 100 compressor-cylinder-supporting portion, a cylinder having its base removably secured to said supporting portion, a piston working in said cylinder, an engine-driven shaft, a driving connection between said piston and 105 said shaft including a connecting-rod having an adjustable big end bearing associated with said shaft, said cover plate being so constructed and arranged relative to said engine crankcase and the base of said cylinder as to 110 permit its removal, upon the removal of said cylinder, for adjustment or inspection of said big end bearing while said bearing is associated with said shaft.

In testimony whereof, I affix my signature.
NIELS A. CHRISTENSEN.
